UNITED STATES PATENT OFFICE.

HUBERT P. IRMITER, OF MINNEAPOLIS, MINNESOTA.

OIL BURNER.

Application filed February 13, 1925. Serial No. 8,888.

This invention relates to an oil burner, and while the invention is applicable to many types of burners, it particularly is designed for use in a cook stove or in a domestic furnace. When used for a cook stove a burner should be of a form which can easily and quickly be installed in the cook stove without any considerable change in the stove and the burner should be one that will 10 give an efficient and wide distribution of the flame.

It is an object of this invention, therefore, to provide a burner for a cook stove or furnace comprising very few parts which are 15 easily constructed and assembled and which may be readily and quickly installed.

It is a further object of the invention to provide such a burner comprising a base tapering toward one end, which end is provided with an air inlet passage, and the 20 other end of which constitutes a basin and an oil supply means.

It is further an object of the invention to provide a burner having a base, as defined in 25 the above paragraph, together with a reversely bent conduit having a substantially 180 degree bend having means fitting over a flange surrounding the air passage of said base and having its other end disposed over 30 the basin and around the upper part of the oil supply means.

It is still another object of the invention to provide a burner having a base formed at its top to constitute a basin by which the 35 flame is deflected, said basin having a plate disposed below the same and largely spaced therefrom.

It is also an object of the invention to provide a burner having a base formed at one 40 end at its top as a deflecting basin, which basin has at its rear side a deflecting rib extending thereacross.

These and other objects and advantages of the invention will be fully set forth in 45 the following description made in connection with the accompanying drawings, in which like reference characters refer to the same parts throughout the different views, and in which,

Fig. 1 is a top plan view of a portion of 50 a stove, the walls of which are shown in section and showing a plan view of the burner therein;

Fig. 2 is a top plan view of the burner;

Fig. 3 is a vertical section taken on the

line 3—3 of Fig. 2, as indicated by the arrows, showing the burner in place on the grate bars of the stove;

Fig. 4 is a vertical section taken on the line 4—4 of Fig. 2, as indicated by the 60 arrows;

Fig. 5 is a vertical section taken on the line 5—5 of Fig. 2, as indicated by the arrows; and

Fig. 6 is a partial view similar to Fig. 3, 65 showing a modified structure.

Referring to the drawings, the burner is shown comprising a base portion 6. This base portion is generally of oblong shape having semi-cylindrical end portions, the 70 side portions being tangent to these end portions. One end of the base is much smaller in transverse direction than the other end and the sides thus converge toward said first mentioned end. The bottom portion of the 75 base is of open formation and the walls thereof are adapted to rest upon the grate bars B of a stove or furnace, the burner preferably being held in place by fire clay or other similar substance C being placed 80 thereabout and over and between the grate bars B which are not covered by the burner. The small end of the base 6 has a passage 6^a extending therethrough, the upper end of which is surrounded by an annular flange 85 6^b having a ledge or shoulder 6^c formed thereabout. The larger or front end of the base is formed at its top as a basin 6^d having upwardly sloping outer sides and a central post 6^e shown as integral with the 90 base rises from the central portion of the basin 6^d. The post 6^e is generally of cylindrical shape and may be formed with a slight upper taper and has its top portion formed of reduced diameter forming a ledge 95 6^f. The post 6^e has a central passage extending therethrough and, also has a small annular groove 6^g in its top surface surrounding said opening. An oil supply pipe 7 is secured in the bottom of the opening in post 100 6^e, and while the same may be secured in any suitable manner, it is shown as threaded into said opening. The post 6^e, as clearly shown in Fig. 3, is somewhat hollow and the same, together with the bottom part of basin 105 6^d, has a plate 8 extending across the same, which plate may be fastened or secured in place in any suitable manner, as by the rivets 6^h formed on the bottom of the basin 6^d. The basin 6^d has a lateral extension to-

ward its rear side, the top surface of which is a slight distance below the top of the basin, and a passage 6^a extends downwardly therefrom, an overflow drain pipe 9 being secured in said opening, as by the screw threads shown in Fig. 5. The basin 6^d also has extending thereacross from the rear side of post 6^e to its rear wall, a deflecting rib 6^k, the sides of which slope downwardly and outwardly to the bottom of said basin. A reversely bent conduit 10 is provided extending through substantially 180 degrees, which conduit is formed at its rear side with a depending shouldered flange 10^a adapted to fit around the flange 6^b and to rest on the ledge 6^f. The inner surface of flange 6^b is flush with the inner surface of the wall of conduit 10 so that an unobstructed passage is formed by the passage 6^a and the passage through the conduit 10. The other end of conduit 10 is open and directed downwardly centrally of the basin 6^d, said end surrounding the upper end of post 6^e.

In the modification shown in Fig. 6, a separate cup-shaped member 11 is used adapted to fit in the basin 6^d and the same has an opening fitting about the post 6^e.

In operation, the burner is installed, as indicated in Figs. 1 and 3. The oil is supplied through the pipe 7 by gravity or other pressure and flows upwardly through the opening in post 6^e and out onto the top surface thereof into groove 6^g. To start the burner, some oil will be placed in the basin 6^d or a piece of oily waste or other combustible matter placed therein. This will heat the post 6^e and the oil issuing at the top thereof will be vaporized. Air passes upwardly through passage 6^a through the grate bars and is directed downwardly about the post 6^e by the conduit 10. This air is thus mixed with the vaporized fuel and an efficient combustible mixture formed which is ignited and the flame produced is reflected and deflected by the walls of the basin 6^d and directed outwardly therefrom about the greater portion of its extent. As the air is directed downwardly at the rear portion of the basin it is deflected to each side on the rib 6^k and the flame will be directed toward the rear or small end of the burner substantially on a line passing through the center of post 6^e and tangent to the rear side of conduit 10. If any unvaporized oil should run over the top of the post 6^e it will spread out on the ledge 6^f and will be here vaporized by the heat of the parts. Trouble has been experienced in some burners by the cold air from the grate bars reaching the heated parts causing the same to crack. To prevent this, a plate 8 is provided which will be made of steel or other heat resisting material. This plate prevents the cold air coming through the grate bars from engaging directly with the bottom of the basin 6^d. Cracking of this

basin, therefore, due to the cold air striking the same is prevented. If, for any reason, oil should accumulate in basin 6^d as when the oil might be flowing with the burner extinguished, the same will pass into the lateral extension of the basin and out through the opening 6^j and pipe 9. It has been found in some previous burners where a separate post or cone is used in a deflecting basin, that owing to the heating and expansion and contraction, the post or cone would get out of axial alinement with the basin. This would cause imperfect action and deposits of carbon. By providing the heavy integral post 6^e, and connecting the pipe 7 directly to the underside thereof, applicant has overcome this serious objection. The post 6^e being comparatively thick and heavy absorbs considerable heat and thus makes an effective vaporizer. The ledge 6^f, as well as deflecting any unvaporized oil which might lodge thereon also acts to deflect the air and thus increases the effectiveness of the mixture of the vapor and air. By having the flange 10^a disposed over the flange 6^b, an unobstructed passage is, as above stated, formed for the air through base 6 and conduit 10. The tapered form or converging sides of the base also constitute an important feature of the burner. As shown in Fig. 1, the burner can be placed with one side of the base against the front wall D of the fire box. It is a common practice to have the front and end wall of the fire box formed as a water heater to which water is supplied to and taken from by the pipes 12 and 13, respectively. By disposing the burner, as shown in Fig. 1, a wide distribution of the flame is secured and a large portion of the front wall, as well as the end wall and rear wall of the fire box will be contacted by the flame. A wider range of flame distribution is thus obtained than would be obtained if the sides of the base were parallel and the transverse dimension of conduit 10 were greater.

In the modification shown in Fig. 6, a separate cup member 11 is used. This may be made as a casting or a stamped or forged plate. When the burner is running at full capacity, the top of the basin 6^d becomes very highly heated and if the metal is not of good quality the basin may be burned out. By providing the simple cup 11 the same can be removed if it becomes distorted and it will not be necessary to supply an entirely new base piece.

From the above description, it is seen that applicant has provided a very simple and efficient burner and one which will have high utility for the purpose intended. The burner comprises very few parts and these can be easily made, assembled and disassembled. The burner can also be quickly and easily installed in a stove or furnace and can readily be removed therefrom, if desired. The

pipe connections are quite simple. The burner has been demonstrated in actual practice and found to be very efficient.

It will, of course, be understood that various changes may be made in the form, details, arrangement and proportion of the parts without departing from the scope of applicant's invention, which, generally stated, consists in a device capable of carrying out the objects above set forth, such as shown and described and in the novel parts and combination of parts disclosed and defined in the appended claim.

What is claimed is:

15. An oil burner comprising a base having

a basin formed in its front end and a cylindrical upstanding post formed in the centre of said basin forming an oil supply means, said base having an aperture in its rear end, a conduit over said aperture and reversely 20 bent to discharge gases over said basin and post when the device is in operation, said base having an upwardly curved and vertical rib extending from the rear side of said post to adjacent said aperture, said rib being adapted to direct the gases issuing from said conduit to either side of said basin.

In testimony whereof I affix my signature.

HUBERT P. IRMITER.
